UNITED STATES PATENT OFFICE.

JOHN F. LEWIS, OF OXFORD, INDIANA.

ATTACHMENT FOR PNEUMATIC STRAW-STACKERS.

SPECIFICATION forming part of Letters Patent No. 643,383, dated February 13, 1900.

Application filed March 18, 1899. Serial No. 708,871. (No model.)

To all whom it may concern:

Be it known that I, JOHN F. LEWIS, a citizen of the United States, residing at Oxford, in the county of Benton and State of Indiana, 5 have invented a new and useful Attachment for Pneumatic Straw-Stackers, of which the following is a specification.

My invention relates to an attachment for pneumatic straw-stackers; and it has primarily for its object to provide a means by which the straw may be deposited at any place desired on the straw rick or stack.

In the ordinary pneumatic stacker the blast carries the straw for a considerable distance 15 beyond the hood on the stacker-tube and the straw is spread over a large area of ground in the absence of means which direct the straw upon the rick or stack. I overcome this objection by providing a baffle or arrester which is suspended in advance of the hood on the stacker-tube and is constructed to deflect the straw toward or upon the rick, and at the same time this baffle permits the blast to pass freely.

25 The deflector of my invention is suspended for adjustment at any desired angle to the plane of the stacker-tube, and it is also constructed to direct the straw on curved lines upon the rick for the purpose of giving a 30 proper shape to the latter. With the baffle is combined means for conveniently adjusting said baffle at different angles to the stacker-tube when the position of the latter is changed in order that the baffle may always be disposed in proper operative relation to the hood 35 of the stacker-tube. Said means for adjusting the deflector is combined with the devices for adjusting the telescopic part of the stacker-tube in order that the adjusting appliance 40 for the deflector may be operated in unison with the adjustment of said telescopic tube, whereby slack in the cable of said deflector may be taken up automatically.

The invention further consists in the novel 45 construction and arrangement of parts, which will be hereinafter fully described and claimed.

To enable others to understand the invention, I have illustrated the preferred embodiment thereof in the accompanying drawings, forming a part of this specification, and in which—

Figure 1 is a side elevation of part of an ordinary stacker-tube with my attachment applied thereto. Fig. 2 is a detail perspective 55 view of the attachment removed from the stacker-tube. Fig. 3 is a longitudinal sectional elevation through the attachment represented by Fig. 2. Fig. 4 is an enlarged view, in side elevation, of the means for adjusting 60 the deflector.

Like numerals of reference denote like and corresponding parts in each of the several figures of the drawings.

The conveyer-tube of an ordinary pneumatic stacker is represented in a general way by Fig. 1 of the drawings, and said tube is indicated by the numeral 10 and its hood by 11. These parts are or may be of any usual construction, and no novelty therefor is 70 claimed in this application, because my invention resides in the employment of a baffle or arrester 12, the detailed construction of which I will now proceed to describe. This baffle or arrester is constructed, essentially, 75 of a carrying rod or bar 13 and a series of fingers 14. In the embodiment of the baffle represented more clearly by Figs. 2 and 3 the carrying-rod 13 is curved or arched in the direction of its length, and at suitable intervals said rod is provided with transverse openings that receive the upper ends of the fingers 14, said fingers being provided with male-threaded ends that receive the nuts for clamping the fingers rigidly to the carrying- 85 rod. The fingers are arranged substantially at right angles to the carrying-rod, and they are curved throughout their length.

The means which I have adopted for supporting the baffle or deflector consists of a 90 pair of bands 15, which are applied to the stacker-tube 10 below the hood 11 thereof, and these bands are secured firmly to the tube by means of bolts 16, which may pass through the bands and tube or which may 95 be disposed to join the ends of the bands together for the purpose of clamping the bands upon the stacker-tube by frictional contact therewith, thus obviating the necessity for passing the bolts through the stacker-tube. 100 To the pair of supporting-bands 15 are secured the supporting straps or bars 17 18, which are disposed on opposite sides of the stacker-tube, said supporting-straps being

fastened to the annular bands by the bolts 19. These supporting-straps are arranged alongside of the stacker-tube and the hood thereof, and said straps are extended in an upward and forward direction beyond the hood 11, whereby the straps are adapted to support the baffle or arrester in a position in front of the stacker-tube hood. The supporting-strap 17 is provided at its front end with an eye or loop 20, which is designed to receive one end of the carrying rod or bar 13; but the other supporting-strap 18 has a transverse opening that receives the opposite end of the carrying-rod 13. Suitable nuts are fitted to the ends of the carrying-rod to loosely confine the latter in the supports provided therefor at the free ends of the supporting-straps 18, and this carrying-rod of the baffle is thus loosely mounted in the supporting-straps, so as to turn or rock thereon, whereby the baffle may be adjusted to different positions with relation to the plane of the stacker-tube.

The means for adjusting the baffle consists of a pulley 21, which is fastened firmly to the carrying-rod 13, at a point intermediate its length, preferably at the middle thereof, and in a position between two of the fingers 14. I employ a pulley having a circumferential groove, and said pulley is provided with an offstanding arm 22. An operating-cable 23 is coiled or wrapped one or more times around the grooved pulley 21 and is made fast therewith by looping said cable on the arm 22. This cable has its strands extending lengthwise of the stacker-tube to a suitable point at or near the inner receiving end of said tube, and said strands of the cable are coiled individually on separate take-up drums forming a part of the mechanism for adjusting the baffle. As is common in the art, the stacker-tube is mounted on and carried by a turn-table 24, (see Fig. 1,) and this turn-table also supports the adjusting appliances for the telescopic hood and the deflector. A main supporting-frame 25 is fastened securely to the turn-table at the base of the stacker-tube, and in this main frame is journaled an operating-shaft 26, one end of which is extended beyond the frame. On said extended end of the operating-shaft is fastened a balance-wheel 27, which is equipped with a hand-crank 28, and the shaft is, furthermore, provided with a sprocket-wheel 30, that is engaged by an endless chain 39, passing over a pinion 40 on an arm 41, said chain being fastened at 42 to the sliding part of the stacker-tube.

As the means for adjusting the telescopic tube are familiar to those skilled in the art, I have not considered it essential to illustrate and describe the same in detail.

One of the features of my invention is an adjustable spool-frame 31, which is mounted loosely on the operating-shaft 26 between the supporting-frame 25 thereof and the hand or balance wheel 27. This spool-frame carries a lever 32, which is fastened on one side thereof in a position to engage with a toothed seg-

ment 33, which is fastened securely to the main frame 25; whereby the spool-frame may be adjusted to different positions on the operating-shaft and made fast by engagement of its lever with the segment.

34 35 designate the take-up spools, which are arranged parallel with each other at opposite ends of the frame 31 and on opposite sides of the operating-shaft 26, and these spools are carried by shafts 36, which are journaled in the adjustable frame. Said spool-shafts are provided with gear-pinions 37, which mesh with a driving-gear 38, secured to the operating-shaft 26 in a position to engage with both of the spool-pinions 37 for the purpose of rotating them and the spools simultaneously. The strands of the cable 23 are led over the top sides of the two spools, 85 and they are coiled in corresponding directions on said spools to be coiled on or uncoiled from the spools simultaneously.

In applying my device to an ordinary pneumatic stacker the annular bands 15 are fastened to the tube in spaced relation to each other and contiguous to the hood 11, and the supporting-straps are fastened securely to these annular bands in positions to extend beyond the extensible hood 11 on said tube. 95 The carrying-rod 13 is loosely mounted in the free ends of the supporting-straps, and the cable 23 is coiled on and looped around the arm of the pulley 21, after which said cable has its strands coiled on the respective pulleys or spools at or near the pivotal support of the stacker-tube.

In the service of the baffle it is suspended directly in front of the hood 11, and said baffle lies above and below the plane of exit of the blast and straw from the stacker-tube and its hood. The blast of air which conveys the straw through the stacker-tube is free to escape and pass through the fingers of the baffle; but the straw is caught and detained by the baffle-bars as the blast expends its energy on the straw when it emerges from the stacker-tube. The straw which is caught by the baffle-fingers is free to drop or fall from the baffle upon the rick or stack, and the straw is thus prevented from being carried by the blast for considerable distances beyond the end of the stacker-tube, and thereby spread over a large area of the ground.

In adjusting the sliding member of the stacker-tube the crank is operated to rotate the shaft, thus turning the sprocket, which actuates the means for changing the position of the sliding tube on the stacker. The rotation of the shaft also operates the gear 38 to turn the spools, and the strands of the cable 23 are paid out from both drums or spools when the stacker-tube is extended. A reverse adjustment of the shaft to contract the stacker-tube coils the cables of the spools, and thus the slack in the cable-strands is taken up. To adjust the deflector, the lever or arm 32 is disengaged from the segment and the arm is moved to tilt the frame in one direc-

tion or the other, thus moving the deflector on its pivotal support and changing its position relatively to the stacker-tube.

In plan view the baffle of my invention has its fingers disposed in an arc, owing to the curvature or arched form of the carrying rod or bar 13, and by this construction the straw is deposited upon the stack on curved lines for the purpose of properly shaping the rick

or stack.

It will be observed that the position of the baffle with relation to the stacker-tube and its hood may be easily changed by the attendant stationed at the machine, who is able to control the operating-shaft 26.

In the practical service of the pneumatic stacker it becomes necessary to frequently change the angle of the stacker-tube as the straw increases in height, and the baffle of my invention is adjustable with the stacker-tube, and it is also adjustable independently of the stacker-tube for the purpose of making the baffle assume a proper operative relation to the stacker-tube when its position is changed.

From the foregoing description it will be observed that the attachment of my invention may be easily and firmly applied to the conveyer-tube of ordinary pneumatic stackers, and the entire attachment is simple and durable in construction and efficient in operation.

Changes may be made in the form and proportion of some of the parts while their essential features are retained and the spirit of the invention is embodied. Hence I do not desire to be limited to the precise form of all the parts as shown, reserving the right to vary therefrom.

Having thus described the invention, what I claim is—

1. In a pneumatic straw-stacker, the combination with the stacker-tube, of fixed supporting-straps attached to the tube and extending upwardly and forwardly from the hood thereon, a baffle or arrester consisting of an arched bar and a plurality of spaced fingers pendent from said bar, the bar being journaled at its ends to said straps, a pulley fast with the arched bar, and an operating-cable having suitable connection with the pulley to provide for oscillating the bar to change the inclination of the baffle, substantially as described.

2. In a pneumatic straw-stacker, the combination with the stacker-tube, of spaced bands fitted to the tube, fixed supporting-straps attached to the spaced bands and ex-

tending beyond the hood of the stacker-tube, a baffle or arrester consisting of a bar journaled in said straps, and a plurality of spaced fingers arranged on the arc of a circle and pendent from the bar, and an adjusting device having an operative connection with the baffle-bar to provide for adjusting the inclination of the latter, substantially as described.

3. In a pneumatic straw-stacker, the combination with the telescopic tube, of a support attached to and extended beyond the outer end of the slidable member of the tube, an adjustable straw baffle or arrester extended from said support, a tilttable frame, take-up spools mounted in said frame, an operating-cable connected with the baffle or deflector and having its strands respectively coiled on the separate take-up spools, and means for simultaneously adjusting the slidable member of the tube and rotating said take-up spools, substantially as described.

4. The combination with a stacker-tube, and a deflector pivotally supported beyond the delivery end of said tube, of an operating-shaft supported at the base of the stacker-tube, a frame mounted idly on said shaft and provided with means for holding the same in a fixed position, take-up spools journaled in said frame on opposite sides of the shaft and geared to the latter to be rotated simultaneously thereby, and an operating-cable connected to the pivoted deflector and having its respective strands coiled on the take-up spools, substantially as described.

5. The combination with a stacker-tube provided with a hood, a pivoted deflector, and means for supporting said deflector beyond the delivery end of said hood, of a frame supporting an operating-shaft, a spool-frame mounted idly on the operating-shaft, a locking device between the first-named frame and the spool-frame, take-up spools journaled in the spool-frame on opposite sides of the operating-shaft and geared to the latter to be rotated thereby, and a cable connected to the pivoted deflector and having its strands coiled on the respective take-up spools, substantially as described.

In testimony that I claim the foregoing as my own I have hereto affixed my signature in the presence of two witnesses.

JOHN F. LEWIS.
